(57) **CLAIM**

The ornamental design for a multi-head bolt, substantially as shown.

DESCRIPTION

FIG. 1 is a perspective view of a multi-head bolt according to a first embodiment;

FIG. 2 is a front view of the multi-head bolt according to the first embodiment;

FIG. 3 is a rear view of the multi-head bolt according to the first embodiment;

FIG. 4 is a right side view of the multi-head bolt according to the first embodiment;

FIG. 5 is a left side view of the multi-head bolt according to the first embodiment;

FIG. 6 is a top view of the multi-head bolt according to the first embodiment;

FIG. 7 is a bottom view of the multi-head bolt according to the first embodiment;

FIG. 8 is a perspective view of a multi-head bolt according to a second embodiment;

FIG. 9 is a front view of the multi-head bolt according to the second embodiment;

FIG. 10 is a rear view of the multi-head bolt according to the second embodiment;

FIG. 11 is a right side view of the multi-head bolt according to the second embodiment;

FIG. 12 is a left side view of the multi-head bolt according to the second embodiment;

FIG. 13 is a top view of the multi-head bolt according to the second embodiment; and,

FIG. 14 is a bottom view of the multi-head bolt according to the second embodiment.

The broken lines in the drawings illustrate portions of the multi-head bolt and form no part of the claimed design. The dot-dash-dot broken lines in the drawings define the bounds of the claim and form no part thereof.

1 Claim, 12 Drawing Sheets
